(57) **CLAIM**

The ornamental design for an ear wax removal tool, as shown and described.

DESCRIPTION

FIG. 1 is a top, front, right side perspective view of an ear wax removal tool, showing my new design;

FIG. 2 is a bottom, rear, left side perspective view thereof;

FIG. 3 is a front and right side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged view of portion 10 in FIG. 1;

FIG. 11 is an enlarged view of portion 11 in FIG. 2;

FIG. 12 is an enlarged view of portion 12 in FIG. 4; and,

FIG. 13 is an enlarged view of portion 13 in FIG. 6.

The dash-dash broken lines in FIG. 1 and FIG. 10 illustrate features of the ear wax removal tool and form no part of the claimed design. The dot-dash broken lines shown in the figures are included to identify areas of enlargement and form no part of the claimed design.

1 Claim, 13 Drawing Sheets
